ATTORNEY

UNITED STATES PATENT OFFICE.

IRAD L. GARSIDE, OF PATERSON, NEW JERSEY.

SLEEVE-BUTTON.

SPECIFICATION forming part of Letters Patent No. 230,473, dated July 27, 1880.

Application filed June 14, 1880. (No model.)

To all whom it may concern:

Be it known that I, IRAD L. GARSIDE, a citizen of the United States, residing in Paterson, Passaic county, in the State of New Jersey, have invented certain new and useful Improvements in Sleeve-Buttons and analogous articles of use and ornament, of which the following is a specification.

I will describe the device as a sleeve-button, and as made of gold or of a suitable metal coated with a precious metal, it being understood that a corresponding device may be made of the same or different size and of the same or different material for shirt-studs and other uses, including ordinary buttons.

The improved sleeve-button is of that class which is made in two parts and applied together in the cuff to avoid the necessity for passing the smaller part, ordinarily termed the "shoe," through the button-hole.

Various devices have been produced for the purpose, the preferable form having a flat stem of a width something less than the length of the ordinary button-hole.

My button has marked advantages. The button is attached and detached by turning one part a portion of a revolution relatively to the other. A spring of proper tension is mounted in the interior of the main part and induces a constant tendency to the locked position. Unlocking only occurs when the parts are forcibly held and turned about a quarter of a revolution, the one relatively to the other, and then drawn apart. This condition will never obtain by accident, but is easily realized without tools and with very moderate skill when it is desired to remove or insert the button.

The accompanying drawings form a part of this specification, and represent what I consider the best means of carrying out the invention.

Figure 1 is a face view of the button, showing that it presents the ordinary appearance without being deformed by any projection. Fig. 2 is a rear view. Fig. 3 is a cross-section. Fig. 4 is a horizontal section, and Fig. 4^a a rear view of a detail detached. Fig. 5 is a section of the shoe and shank to be attached and detached in securing and releasing the button. Fig. 6 is a modification shown in section.

Similar letters of reference indicate corresponding parts in all the figures.

A represents the face and rim of the button; A', a middle plate having a peculiarly-shaped aperture, to be described farther on, and A² a back plate having a considerable circular hole in the center. A plate, B, is fitted to turn between the plates A' and A², and is formed with a narrow slot, which receives a flat tube, B', firmly soldered, so as to form a single piece therewith. This tube reaches inward through a hole in the plate A', and is notched at the points m to engage with the plate A' when turned in certain positions.

G is the shoe, and G' a flat shank adapted to match in the interior of the flat tube B'. It reaches through this tube, and is notched at the points g to correspond with the notches m in the tube.

The form of the orifice a in the plate A' is such as allows the flat tube B' to turn a quarter circle in one direction. It is, furthermore, such that when the tube B' and its inclosed shank G' is turned to one extreme position the shank can be freely drawn out; but when turned to the other extreme position the shank is locked by the engagement of its notch with the metal of A'.

A spring, D, is coiled in the interior of the button and engaged by one end with the fixed part of the button and by the other with the flat tube B'. It tends to turn the tube B' and its connections with considerable force into the position which will hold the inclosed shank G' locked.

The action will now be readily understood. The button being placed in position on one side of the cuff, the shoe G is applied to the other side and its shank or post G' inserted through the button-hole in the cuff into the tube B' of the button. While the last of the inserting movement is being effected the shoe is turned relatively to the button, the button being actually turned by the force of the thumb and fingers about a quarter revolution, the plate B and tube B' standing still, and thus being caused to turn within it a quarter revolution. This brings the parts into a position where the shank G' may be thrust fully home. The button being liberated in this position, the force of the spring D instantly gives it a

quarter revolution and brings the notches *g* into engagement with the metal of *A'*. The button and the shoe are now locked together. They will remain locked until the button is again forcibly turned a quarter revolution.

5 This movement is easily effected, when it is desired, in liberating the button; but it is very unlikely to occur by any accidental strain.

To facilitate the attachment of the spring 10 *D* to the tube *B'*, I apply a circular plate, *B²*, of considerably area. This may be soldered or otherwise permanently fastened to the inner end of the tube *B'*. The spring *D* may be easily attached to it by ordinary means.

15 I prefer that the plate *B'* have a raised center of slightly less diameter than the circular hole in the plate *A²*, as shown. This forms a handsome finish and gives a reliable steadiness to the position of all the parts.

20 I prefer that the tube *B'* shall extend outward, as shown, to a distance about equal to the double thickness of an ordinary cuff.

I prefer that the plate *A'* be manufactured, independently of the other parts, with a rim 25 or flange, as shown, and be firmly set in the interior of the button by soldering or other approved means; but this may be varied.

Many modifications may be made in the proportions and forms of the details. I prefer to 30 use a spring, *D*, of sufficient length to coil three or more times quite around in the interior of the button, after the manner of the mainspring of a watch. This facilitates giving a long action to the spring with gentle force. It also avoids overstraining the metal 35 of the spring and promotes the durability of the device. Other forms of spring may be used, if preferred.

I have shown the body *A* as formed by a 40 stone with a rim as a setting. This may be varied indefinitely. The exterior form of the button need not be circular. It may be made of any ordinary or suitable pattern, so long as it provides for the quarter turning of the tube

B' and its connections, and affords the required locking means and space for the spring. The plate *B* and tube *B'*, as also the attached spring *D*, may be made from a single piece of hard brass properly worked.

Fig. 6 is a cross-section representing a modification which is preferable, for some reasons, to the form first shown. The same parts are indicated by the same letters as before, but the forms are considerably varied. The flat tube *B'* does not project out of the back of the bottom, but the shank or post *G'*, attached to the shoe *G*, is made wider outside, so as to present a proper shoulder and prevent the parts being forced too far in. The spring *D* is in this modification located between the plate *A'* and the plate *A²*. In this modification the plate *B²* is greatly contracted in diameter, but it has still sufficient area to perform its function of locking the tube *B'* within the button by allowing it to turn freely.

65 I claim as my invention—

1. The shoe *G*, having a shank, *G'*, and notch or offset *g*, in combination with the button *A*, having the peculiarly perforated middle plate, *A'* *a*, and with the volute spring *D* 70 exerting a force to turn the shank axially around, and to hold it engaged, as herein specified.

2. The turning plate *B* and flat tube *B'*, with its notches *m*, in combination with the button *A*, having two plates, *A'* *A²*, perforated, as shown, and with the spring *D*, all adapted to serve relatively to each other and to a properly-formed shank as and for the purposes 75 herein specified.

In testimony whereof I have hereunto set my hand at New York city this 2d day of June, 1880, in the presence of two subscribing witnesses.

80 I. L. GARSIDE.
